UNITED STATES PATENT OFFICE.

DANIEL TAINTER, OF WORCESTER, MASSACHUSETTS.

IMPROVEMENT IN WOOL-CARDING MACHINES.

Specification forming part of Letters Patent No. 40,131, dated September 29, 1863.

To all whom it may concern:

Be it known that I, DANIEL TAINTER, of Worcester, in the county of Worcester and State of Massachusetts, have invented certain new and useful Improvements in Wool-Carding Machines; and I do hereby declare that the following is a full, clear, and exact description of the same, reference being had to the accompanying drawings, forming a part of this specification, and in which—

Figures 1, 2, and 3 represent the sides of the common or ordinary cast-iron frames of the first breaker, second breaker, and finisher of wool-carding machines, respectively, while Figs. 4, 5, and 6 represent the sides of the frames of the same machines as improved by me. Figs. 7 and 8 represent detached parts, and will be referred to hereinafter.

The reason why wool-carding machine-frames are made different lengths for first and second breakers and different length on "doffer" end of finisher is, first, the first breaker has much more machinery and gearing on or attached to the feed end A of the machines than the second breaker and finisher have. To the first breaker are attached the feed-apron and burring-machine, which are supported on the horizontal part of the frame A. The second breaker and finisher, having no feed-apron or burring-machine attached, are made shorter than the first breaker, as indicated in Figs. 5 and 6. The doffer end B of the finisher-card, where the condenser is put on, must be lower down to receive the condenser than the doffer end to the breakers, and also shorter. Consequently all three frames to a set of wool-carding machines are made differently, and required different patterns as previously made.

The arch C of a wool-carding machine is commonly made with two flanges or ribs, D E, for the purpose of supporting the "puppet-heads" (so called) or stands e, in which the bearings or journals h rest or run. Said stands or puppet-head stems, being fitted to a cap or casting, a, screwed or bolted on top of the arch, the lower ends passing through holes in the flange E of the arch C.

My first improvement relates to a plan or device to save the expense of drilling, cutting, or coring the holes in the top or outside flange, while at the same time securing the proper and necessary bearings for the puppet-head

stems. This I accomplish by cutting notches, openings, or spaces in my arch-pattern on the top or outside flange, so as to have an open space (at such places as it may be desirable to put in the puppet-head stems) cast in said arches, in connection with the use of the peculiarly-constructed cap-pieces a, which are so made that the molding or bead c fits into the outer edge of the opening in the flange D, while the ends of the cap-piece a rest upon the top surface of the same flange, thereby making a lock joint or connection, which insures the permanent relative position of the cap-piece and puppet-head stems as respects the main cylinder G, which is supported in bearings upon the iron frame F.

In Figs. 4, 5, and 6 a cap, a, with its molding or bead c, is shown in place, while in Fig. 8 three views—viz., a top or plan, side, and central or cross-section—of the cap a are given, showing all the parts on an enlarged scale.

To the central and main part, F, of the frame I attach ends, arms, or wings A and B, of such length and pattern as are rendered necessary by the kind of card or machine ordered.

In constructing a card-frame with each side in three separate pieces, I found a difficulty in attaching the two ends, arms, or wings A and B to the main portion of the frame F, since these ends, arms, or wings had a great tendency to sag or draw off from the main portion of the frame, and thus throw the machinery supported thereon out of line and its relative and proper position as respects the main cylinder G. In order, therefore, to secure the arms or wings to the main part F in such a manner that they would always retain a fixed relative position, I constructed or formed the wings or arms A and B with ear-pieces i i, to project by and bear against the inside of the main frame F, and also with a hook or projection, f, to fit into a corresponding notch or hook, d, formed on the main frame, all as clearly indicated in Fig. 4 of the drawings.

By reference to the drawings it will be seen that as the arms or wings are dropped down into position, owing to the flaring of the bottom of the frame F against the edges of which the ends of the wings bear, and the wedge-like form of the hooks or projections f, a very close and secure joint and connection is obtained even without the use of bolts,

and one, too, that will sustain the arms or wings from any downward deflection, thereby insuring a fixed and permanent relative position of the wings and the machinery connected therewith during the operation of the machine.

In Fig. 7 one of the end pieces is shown on an enlarged scale, and from which it will be seen that with bolts passing through the ear-pieces *i i*, in combination with the hooks *d'* and *f*, a good, firm connection with the main part *F* of the frame, is obtained, and one, too, that permits the use of loosely-fitting bolts.

Having described my improvements in wool-carding machines, what I claim as of my invention, and desire to secure by Letters Patent, is—

1. The combination, with the flange *D*, when cut or cored out as described, of the peculiarly-constructed arch cap-piece *a*, with its head or molding *c*, as and for the purposes set forth.

2. The combination of the ears *i i* and hooks or angular projections *f* with the wings or arms *A* or *B* and hooks or notches *d'* upon the main frame *F*, for the purpose of retaining the wings or arms *A* or *B* in their proper and relative positions, as described.

DANIEL TAINTER.
